UNITED STATES PATENT OFFICE.

SAMUEL H. MERRILL, OF FAIRMONT, MINNESOTA.

DESIGN FOR A SCRAPER.

SPECIFICATION forming part of Design No. 30,291, dated February 28, 1899.

Application filed January 10, 1899. Serial No. 701,761. Term of patent 7 years.

To all whom it may concern:

Be it known that I, SAMUEL H. MERRILL, a citizen of the United States, residing at Fairmont, in the county of Martin and State of Minnesota, have invented and produced a new and useful Design for a Scraper, of which the following is a specification, reference being had to the accompanying drawings, forming part of this specification, in which—

10 Figure 1 is a perspective view of a device constructed in accordance with my design. Fig. 2 is a top edge view, Fig. 3 is an end view, and Fig. 4 is a detail sectional view, of the blade.

15 The essential feature of my design consists in the peculiar shape of the blade, also the handle connected thereto.

Referring particularly to the drawings, A indicates the blade, which is curved substantially upon the arc of a circle, as shown in Fig. 2, said blade being wider at the top than at the bottom, as shown in Fig. 4, and has a slight upward extension or projection along the outer edge, as most clearly shown at A',

the lower edge being rounded, as shown at A². 25 The handle B has the rounded or beaded upper and lower portions B' and the central or web portion B², said web portion having a hole B³, produced therein adjacent to the end of the handle. 30

A scraper constructed in accordance with my design possesses novelty in regard to shape and also possesses great utility.

By means of the design constructed in accordance with my invention I am enabled to 35 scrape every portion of a pot, pan, or kitchen-sink, and owing to the flexibility of the blade the operations can be accomplished with great facility.

Having thus fully described my invention, 40 what I claim as new, and desire to secure by Letters Patent of the United States, is—

The design for a scraper, substantially as herein shown and described.

SAMUEL H. MERRILL.
